[57] **CLAIM**

The ornamental design for camera for video tape recorder, as shown and described.

DESCRIPTION

FIG. 1 is a front, top and right side perspective view of a camera for video tape recorder showing our new design;

FIG. 2 is a rear, bottom and left side perspective view thereof;

FIG. 3 is a front elevational view thereof, with the handle in an upward position;

FIG. 4 is a rear elevational view thereof;

FIG. 5 is a front, top and right side perspective view thereof with the view finder removed;

FIG. 6 is a rear, bottom and left side perspective view thereof;

FIG. 7 is a front elevational view thereof, with the handle in an upward position;

FIG. 8 is a rear elevational view thereof;

FIG. 9 is a front, top and right side perspective view of a second embodiment of the design illustrated in FIG. 1, wherein the lens is larger.

FIG. 10 is a rear, bottom and left side perspective view thereof;

FIG. 11 is a front elevational view thereof, with the handle in an upward position;

FIG. 12 is a rear elevational view thereof;

FIG. 13 is a front, top and right side perspective view thereof with the view finder removed showing our new design as a further variant thereof;

FIG. 14 is a rear, bottom and left side perspective view thereof;

FIG. 15 is a front elevational view thereof, with the handle in an upward position; and

FIG. 16 is a rear elevational view thereof.
